FIG. 1

FIG. 2

FIG. 3

FIGURE 1 is a front perspective view of a combined lounge chair and dual loudspeaker unit showing my design, the side opposite that shown being the same in appearance;

FIGURE 2 is a side perspective view thereof with the base shown in ghost outline in FIGURE 1 eliminated for the sake of clarity; and

FIGURE 3 is a rear perspective view thereof with the base shown in ghost outline in FIGURE 1 eliminated for the sake of clarity.

The dominant features of my design reside in those portions shown in full lines in the drawings.

I claim:

The ornamental design for a combined lounge chair and dual loudspeaker unit, as shown and described.
